UNITED STATES PATENT OFFICE.

IVAR A. RANDEL, OF CHICAGO, ILLINOIS.

TRUCK-FRAME.

1,097,045.

Specification of Letters Patent.

Patented May 19, 1914.

Original application filed February 10, 1912, Serial No. 676,798. Divided and this application filed April 12, 1913. Serial No. 760,610.

To all whom it may concern:

Be it known that I, IVAR A. RANDEL, a citizen of the United States, residing at Chicago, in the county of Cook and State of Illinois, have invented certain new and useful Improvements in Truck-Frames; and I do hereby declare the following to be a full, clear, and exact description of the invention, such as will enable others skilled in the art to which it appertains to make and use the same.

My invention relates to the construction of truck side frames from commercial rolled steel or iron beams.

Particularly, this invention is intended as an improvement on the structure disclosed and claimed in Letters Patent of the United States, No. 1,006,549, granted to Alonzo H. Hastings, of date, October 24th, 1911, and is filled as a division of my pending application Serial Number 676,798, filed February 10th, 1912, and entitled "Process of producing truck frames."

The invention is illustrated in the accompanying drawings, wherein like characters indicate like parts throughout the several views.

Referring to the drawings: Figure 1 is a side elevation showing a completed truck side frame made in accordance with my invention; Fig. 2 is a plan view of the parts shown in Fig. 1; Fig. 3 is a horizontal section taken on the line $x^3 x^3$ on Fig. 1, some parts being broken away; Fig. 4 is a vertical section taken on the line $x^4 x^4$ on Fig. 1; Fig. 5 is a view corresponding to Fig. 1, but illustrating certain features in the development of the completed side frames; Fig. 6 is a side elevation showing the two main frame elements, to-wit; the top and bottom truss members of the side frame, as they appear after having been stamped from a commercial I-beam, and before they have been bent and intimately connected; Figs. 7 and 8 are views, respectively, in plan and end elevation showing the spring plank saddle removed from the truck side frame; Figs. 9, 10 and 11 are views, respectively, in side elevation, face elevation, and plan, showing one of the column guides as it appears immediately before it is applied in the side frame; Fig. 12 is a side elevation showing a commercial I-beam from which the side frame is constructed; Fig. 13 is a view corresponding to Fig. 12 but showing, by cross-

hatch lines, the blanks that are punched from the web of the I-beam as an initial step in the construction of the side frame; Figs. 14 and 15 are views, in diagrammatic plan, illustrating the manner in which blanks for the spring plank saddle and for the column guides are stamped or cut from blanks punched from the web of the I-beam; and Fig. 16 is an end elevation showing a modified form of the transom.

The construction of the truck side frame will be made clear by the description of the manner in which the improved process is carried out to form the said side frame.

The numeral 1, Figs. 12 and 13, indicates a large and heavy commercial form of rolled I-beam, from the web of which, flat blanks 2 and 3 are punched out, leaving vertically alined but separate web portions 4 that are adapted to form the webs of the frame columns. The web portions 5 punched from between the vertically alined column webs 4 might be separately punched, or punched as a part of either of the blanks above noted, but, as shown, they are punched as a part of the blank 2. The very important purpose of severing the column forming webs 4 by the removal of the intermediate portion thereof will be hereinafter made clear.

In Fig. 13, the upper portion of the I-beam which is contained between the points marked $y-y$, is adapted to form the top arch bar or compression member 6 of one truck side frame, while the lower portion thereof contained between the points marked y^1-y^1 is adapted to form the bottom arch bar or tension member 7 of said truck side frame.

In form, the column guides employed in this truck are preferably very much like the form disclosed in the said prior Hastings Patent No. 1,006,549, but they involve this highly important feature of improvement, that they are made of such vertical dimensions and are so constructed that they interlock at their upper ends with the web of the compression member 6, and at their lower ends, with the web of the tension member 7 of the side frame, and thereby very greatly increase the rigidity of the side frame. Also, as a further feature of the improvement over the said Hastings patent, these bolster columns are bent and formed from the blanks 3 which were punched from the web of the original I-beam. The punch

ing of the blank 2 from the web of the I-beam affords a space for the bolster column, and the blanks 2 and 3 are both of the same vertical width. It is evident that column 5 guides formed from blanks cut from the web of the I-beam will have sufficient vertical dimensions to interlock at their upper and lower ends with the webs of the compression and tension members of the truck side frame, 10 only when they are cut from an I-beam primarily having greater depth than the depth or maximum vertical dimension of the completed truck side frame. Hence, the 15 obvious importance of severing the upper and lower members of the I-beam and cutting portions from the webs 4 which are left to form the webs of the frame columns. To illustrate the above point more clearly, it may be stated that in a fifty-ton car, a 20 24-inch I-beam can be used. The space required between the top and bottom, or in other words, the compression and tension members of the side frames is approximately 18 inches, and the depth of the side 25 frame should be approximately 22 inches at the center or intermediate portion. Otherwise stated, about 2 inches is cut from between the sections of the column webs 4 and the top and bottom members are 30 brought about 2 inches closer together. Hence, when the column guides are made from the punched blanks 3, they are overlapped, at their upper and lower ends, one inch with the web flanges of the top and 35 bottom members of the side frame. Fig. 15 illustrates the manner in which the blanks for two of these column guides 8 are punched from a single punched blank 3. These blanks for the column guides are 40 preferably formed with extensions 9, which are adapted to form brake hangers, and at their upper and lower edges, they are formed with notches 8^a that are adapted to receive the web flanges of the top and bottom members 45 of the side frames, and to interlock therewith, as already indicated. Figs. 1, 2, 3 and 4 show the column guides bent into form and applied to the column webs 4. In Fig. 11, full lines show one of the column 50 guides bent nearly into shape, but with the lower flanges and the brake hanger arm 9 left in position, which makes it an easy matter to apply the column guides to the column webs 4. The column guides are then 55 applied, as shown in Fig. 5, and are rigidly secured thereto, in a suitable manner, but preferably by welding the same with what is known as electric spot welding, in which case, spot welds 10 are placed right over the gaps between the abutting ends of the column webs 4, thus securing them together and to the embracing flanges of the column guides. Other spot welds 10^a are preferably placed above and below the welds 10, to further secure the flanges of the column guides

to the column webs 4. The brake hanger arms 9 and the lower flanges of the column guides 8 are then pressed into the position as shown in Figs. 1, 2, 3 and 4, and indicated by dotted lines in Fig. 11.

70

The blank for the spring plank saddle is punched from the blank 2, (see Fig. 14), wherein the cross-hatch lines indicate the portions that are cut off from the said blank 2, to form the blank for the said spring plank saddle. The spring plank saddle is formed by folding the blank 2 approximately as shown in Figs. 7 and 8. The undeturned ends of the saddle 11 are spaced apart far enough to straddle the web of the bottom or tension member 7 of the frame, and it rests on the flanges of the said member 7 and interlocks therewith. The saddle 11 is riveted, or otherwise rigidly secured, to the horizontal flanges of angle iron cross transoms 12, the upper flanges of which are riveted, or otherwise rigidly secured, to the lower flanges of the column guides 8. Preferably, the lower end portions of the column guides are off-set, as best shown in Figs. 1 and 5, and fillers 13 are interposed between the lower flanges thereof and the vertical flanges of the transoms 12. The angle transoms 12 afford the desired cross tie between the lower portions of the two truck side 95 frames, but it is obvious that this cross tie might take different forms, and might, for instance, be formed by a channel beam, as shown in Fig. 16.

85

90

95

100

The order in which the different steps of this improved process may be carried out may be varied somewhat, but preferably, the order is as follows: First, punching out the blanks from the I-beam, as indicated on Fig. 13. Second, cutting the top and bottom members to proper length, as also indicated by letters y and y¹, shown in Fig. 13. Third, bending ends of top and bottom members, as shown in Fig. 6, and bringing the horizontal upper and lower portions of the said members 6 and 7 closer together, so that the ends of the column webs 4 are brought together, as shown in Fig. 5. The side frame is thus formed at its widest point, to-wit, at its intermediate section, with a vertical dimension that is considerably less than the vertical dimension of the I-beam from which it is formed. Fourth, punching out blanks for column guides, as shown in Fig. 15. Fifth, bending column guides into shape, as shown in Figs. 9, 10 and 11. Sixth, placing column guides in their proper location in relation to the top and bottom members, (6 and 7), after remaining web portions 4 have been brought in contact with each other. Seventh, spot welding the column guides to the above mentioned web portions, as indicated on Fig. 5. Eighth, welding the ends of the top and bottom truck members together, completing the truck frame proper.

105

110

115

120

125

130

Ninth, bending the brake hanger brackets 9, and the spring plank brackets on the column guides into proper position. Tenth, stamping out the spring plank or spring angle 5 saddle 11, as shown on Fig. 14. Eleventh, bending this spring plank saddle into shape, as shown in Figs. 7 and 8.

A truck frame constructed in accordance with my invention, above described, will 10 have a large amount of strength with a small amount of metal, and the strength of the same is very greatly increased by interlocking engagement of the column guides with the top and bottom, or compression 15 and tension members of the said frames. Furthermore, as a result of my improved process, great economy is effected, by the elimination of practically all waste of metal, substantially the entire web portion of the 20 original I-beam being utilized in the formation of the column guides and spring plank saddles of the truck.

What I claim is:

1. A truck side frame having upper and 25 lower members and column webs and provided with column guides applied to the

webs with their upper and lower ends overlapped and interlocked with the top and bottom members of said side frame, and a saddle applied to the bottom frame member 30 between said column guides and rigidly connected to said column guides.

2. A truck side frame having upper and lower members and constructed from a commercial I-beam having bottom webs formed 35 from the web of said beam, and provided with channel-shaped column guides that embrace the said column webs and are notched at their upper and lower ends, so that they overlap with and are interlocked to the 40 webs of the said top and bottom frame members, a saddle applied to the bottom frame member between said column guides, and a cross tie rigidly secured to said saddle and to the lower portions of said column guides. 45

In testimony whereof I affix my signature in presence of two witnesses.
